UNITED STATES PATENT OFFICE.

ISAAC L. UMSTEAD, OF IONE CITY, CALIFORNIA.

SUPPORT FOR CARRIAGE-TOPS.

SPECIFICATION forming part of Letters Patent No. 314,631, dated March 31, 1885.

Application filed January 5, 1885. (No model.)

To all whom it may concern:

Be it known that I, ISAAC L. UMSTEAD, of 5
Ione City, Amador county, State of California,
have invented an Improvement in an Adjust-
able Support for Carriage-Tops; and I hereby
declare the following to be a full, clear, and
exact description of the same.

My invention relates to the class of carriage-
tops which are adapted to be raised and thrown
10 back, and to certain improvements in the means
for supporting them.

My invention consists in a peculiar adjust-
able or extensible rod, one on each side of the
15 top, journaled at its lower end on the arm of
the shifting-rail and pivoted at its top to the
rear bow of the carriage-top; and it further
consists in certain details of construction re-
lating to an eccentric bearing of the lower end
20 of the rod, its various adjustments, means for
holding it, when necessary, and preventing
rattling, all of which I shall hereinafter fully
explain.

The object of my invention will be made to
appear in the course of the specification.

25 Referring to the accompanying drawings,
Figure 1 is a perspective view of the body and
top of a buggy. Fig. 2 is a side elevation of
same, showing the top thrown back. Fig. 3
is a perspective view of my extensible rod.

30 I have illustrated my invention in connec-
tion with an ordinary buggy-top, although it
is applicable to any carriage-top which is
adapted to be thrown back.

A is the body of a buggy, and B is its seat.
35 C is the usual shifting-rail encircling the seat,
and D is the arm which projects laterally and
horizontally on each side from the side of the
rail at its back. E is the top, the bows F of
40 which on each side converge downwardly and
are linked together or jointed to the front ends
of the shifting-rail in the usual manner. G
is the long-jointed stay, and H is the short-
jointed stay, arranged with relation to each
45 other and to the top in the ordinary way.

The top E is thrown back by bending the
50 jointed stays, and when moved back to its
limit the rearmost bow on each side lies upon
the arm D, and these two bows bear the weight
of the top.

55 The distance between the center of move-
ment—namely, where the bows join the front of
the shifting-rail, and the point of contact be-
tween the rear bows and the arms D is so much
shorter than the distance between the said

point of contact and back end or top of the 55
bows, that the latter distance becomes a lever
through which almost the entire weight of the
top (which is back of the bearing-point) acts
against the front bearing and upon the sup-
porting-bows. The effect of this is to wrench 60
the front connection, but more especially to
break the supporting-bows. On rocky or un-
even or rough roads where the top is jarred
and thumps upon the arm D, these effects are
constantly following, and are a source of great 65
annoyance and expense, for, in repairing, the
entire bow must be removed and a new one
substituted.

It is the object of my invention to overcome
this difficulty by removing the bearing from 70
the bows, and substituting a more suitable
support which is capable of bearing without
injury the weight of the top, no matter to what
jarring or thumping it may be subjected. Ac-
cordingly I employ an extensible rod, I. The 75
lower end of this rod I pivot on the arm D
between the bearing of the long-jointed stay
and the rail, and its upper end I pivot either
directly or through the intervention of a
suitable iron, i, to the top of the rear bow. 80
There is one such rod on each side. The rea-
son for the extensibility of the rod I is that
the center of motion of the top does not co-
incide with that of the rod, and therefore, in
lowering the top the rod must shorten, as in 85
Fig. 2, and in raising the top it must lengthen,
as in Fig. 1. The limit of contraction of the
rod I is so regulated that it shall hold the top
in the proper inclined position, as shown in
Fig. 2, where the rod has itself an upward in- 90
clination, thereby acting as a strut-brace to
support the top, which cannot move farther
down, because the rod cannot shorten any
more. The rod therefore supports the top,
and the bows are held clear of the arm D, so 95
that they cannot be broken, nor can their con-
nection in front be wrenched or injured in
any wise.

There are several ways in which the rod I
may be constructed so as to render it extensi- 100
ble, but for the purpose of its various adjust-
ments (the reasons for which I shall explain
as I proceed) I prefer the following: The rod
I consists of two main sections, the lower, m,
being tubular, and the upper, n, being a spin- 105
dle or steel rod adapted to telescope into the
lower and to find its limit of movement in the
lower end of the tube. The tube m may be

integral, if desired; or, better, it may consist of two parts, the lowermost, m' , being made of malleable iron and provided with an internal thread at its upper end, into which the 5 externally-threaded lower end of the portion m is screwed, which said portion can be of gas-pipe.

Now, as to the bearing or journal by which the lower end of rod I is pivoted on arm D, 10 if a set of supporting-rods were required for a specific buggy they could be made exactly for the top, and the journal could be an ordinary one formed by the eye o on the base of the rod; but as the tops of buggies differ to 15 some extent in height, it is necessary, in order to manufacture the rods in quantity, that they shall have as much adjustment as possible, so as to fit any top. The principal adjustment of this character I obtain by the employment of a disk, J, which is secured upon the arm D eccentrically. Upon this eccentric the eye o of the rod is pivoted, and is secured by suitable side flanges. By changing the position of the eccentric on the arms the rods may be shortened 20 or lengthened by so much to suit particular tops, so that in some cases the spindle will not reach its limit too soon, and in others will not be drawn out from the tube entirely. The second adjustment, though but a partial one, 25 is found in the screw-connections between the base m' and the portion m . In order to prevent rattling between the spindle n and the tube m , I have the following: Upon the upper portions of the tube are secured, by set-screws p , two collars, P, between which extends a bar, Q. Through the bar a small screw, R, passes, having on its end a small cushion or rubber pad, r, which bears upon the spindle, a slot being made in the tube 30 through which this contact takes place.

If for any reason the top of the tube has subsequently to be cut off, it will be observed that by loosening the set-screw p the collars P and the whole device can be adjusted lower 45 down.

Some may prefer to have the rod I act as a support to the top when raised as well as when thrown back. In such a case I provide the top of the tube m with a small spring or pawl, 50 s , which is adapted to engage with notches or teeth s' , formed on the spindle. When such a device is used, it will of course require the use of both hands to lower the top—one being engaged with the top and the other in disengaging the spring s .

Having thus described my invention, what I claim as new, and desire to secure by Letters Patent, is—

1. An adjustable supporter for swinging carriage or buggy tops, consisting of an extensible rod, bar, or brace—one on each side near the back—pivoted at its lower end to the arm of the shifting-rail or other suitable portion of the body and pivoted at its upper 65 end to the bow of the top, substantially as herein described.

2. In combination with the swinging top of a carriage or buggy having bows jointed to the front of the shifting-rail, an extensible rod, bar, or brace—one on each side—pivoted 70 at its lower end to the arm at the back of the shifting-rail and at its upper end to the top of the rear bow, whereby said rod, bar, or brace is adapted to support the top when thrown back, substantially as herein described. 75

3. The supporter for swinging carriage or buggy tops, consisting of the telescopic rods I, pivoted below on the arms of the shifting-rail and above to the rear bows of the top, substantially as and for the purpose herein described. 80

4. In combination with a swinging carriage or buggy top and the shifting-rail C, to which its bows are jointed, said rail having arms D at the rear, the telescopic rods or braces I, 85 consisting of the tubes m , having an eye by which their lower ends are pivoted on the arm D, and the spindles n , sliding in the tubes and pivoted to the rear bows of the top, substantially as herein described. 90

5. In combination with the swinging carriage or buggy top, the telescopic rods or braces I, formed of the tubular base m' , having eye o , by which it is pivoted on the arm of the shifting-rail, the tubular center m , screwed to 95 the base, and the spindle n , sliding in the tubular base and center and pivoted to the top of the rear bows, substantially as and for the purpose herein described.

6. The swinging top E of a carriage or buggy, shifting-rail C, having arms D at its rear, and the eccentric disks J on said arms, in combination with the extensible or telescopic rods or braces I, pivoted below on the eccentric and above to the rear bows of the top, 105 substantially as herein described. 100

7. In combination with the swinging carriage or buggy top, the telescopic rods or braces I, pivoted below on the arms of the shifting-rail and above to the rear bows of the top, and 110 the means by which the rattling of said rods is avoided, consisting of the collars P, on the outer section of the rods, the bar Q, between the collars, and the cushioned screw R, passing through the bar and through slot in the outer 115 section and bearing against the inner section, substantially as herein described.

8. In combination with swinging carriage or buggy top E, the telescopic rods or braces I, pivoted below on the arm of the shifting-rail and above on the rear bows of the top, 120 and the means by which the rods are made to act as supports for the top when raised, consisting of the spring or pawl s on the outer section and the notches or teeth s' on the inner section, substantially as herein described. 125

In witness whereof I have hereunto set my hand.

ISAAC L. UMSTEAD.
